UNITED STATES PATENT OFFICE

2,514,512

FORCE LASTING MACHINE

John William Pratt, Leicester, England, assignor
to United Shoe Machinery Corporation, Flem-
ington, N. J., a corporation of New Jersey

Application October 22, 1948, Serial No. 56,019
In Great Britain November 8, 1947

7 Claims. (Cl. 12—1)

1

This invention relates to force lasting machines and it is herein disclosed as embodied in a force lasting machine of the type illustrated and described in a copending application for United States Letters Patent Serial No. 24,524 filed May 1, 1948 in the name of Cecil H. Freer, in which application an improved machine for and method of force lasting shoes are broadly claimed. That machine is adapted to operate upon a partially completed platform shoe which may consist, for example, of a shoe upper, a sock lining, and a platform cover, all stitched together to form a unitary assembly. This partially completed shoe is mounted loosely upon a last and the function of the machine is to urge the shoe further heelwardly upon the last. To this end the heelward portion of the platform cover is turned heightwise away from the last to form a pocket and the machine is provided with a member which engages within this pocket and which, when operated, exerts a heelward thrust against the upturned platform cover.

The present invention is in the nature of a further development of, and improvement upon, the Freer machine, and its object is to provide a force lasting machine which not only urges the shoe heelwardly upon its last but which also operates upon the platform cover in such a manner as to prevent subsequent undesirable lengthwise contraction of the shoe.

In accordance with a feature of the invention, the illustrated machine is provided with means for first forcing a shoe heelwardly on its last and then for reversing heightwise the position of the heel end of the platform cover to cause it to hug the heel end of the last and thereby prevent undesirable forward creeping, and consequent loosening, of the shoe on the last. The means for forcing the shoe heelwardly comprises a member curved to conform to the outline of the heel end of the shoe and adapted to engage within the pocket formed by the platform cover. In the illustrated machine this member is shaped like a shoe horn.

In accordance with a further feature, the illustrated machine may be provided with means for gripping the platform cover or for clamping the platform cover against the member which engages within it to exert a rearward thrust. The purpose of such gripping or clamping means is to prevent platform covers of readily stretchable material from deforming and thereby becoming disengaged from the heelward thrusting member.

These and other novel features of the inven-

2

tion are illustrated in the accompanying drawings and hereinafter described and claimed.

Referring to the drawings,

Fig. 1 is a side elevation of an illustrative machine in position to begin operation upon a partially completed shoe assembly;

Fig. 2 is a plan view of a portion of the mechanism shown in Fig. 1;

Fig. 3 is a side elevation of a portion of the mechanism shown in Fig. 1 at an intermediate stage of the operation;

Fig. 4 is a view similar to Fig. 3 showing the positions of the various members at the completion of the operation;

Fig. 5 is a side elevation of a modified form of the machine;

Fig. 6 is a plan view of a portion of the mechanism shown in Fig. 5;

Fig. 7 is a side elevation of a portion of the mechanism shown in Fig. 5 at an intermediate stage of the operation;

Fig. 8 is similar to Fig. 7 showing the positions of the various members at the completion of the operation; and

Fig. 9 is an enlarged elevation showing the arrangement of certain parts.

As shown in the drawings, the partially completed shoe assembly to be operated upon consists of a forepart upper member 10, a heel end upper member 12 having a heel strap 14, a forepart platform cover 16, a heel end platform cover 18, and a sock lining 20 (Fig. 2) to which the upper members and the platform cover members are united by a peripheral seam 22 (Fig. 1). This partially completed shoe assembly has been loosely mounted upon a last 24 which is supported in inverted position upon a last pin 26. The last pin 26 is secured in a standard 28 rising from a base 30 which is securely bolted to a work bench 32. Clamped to the upper portion of the standard 28 is a bracket 34 having an upstanding saddle 36 which embraces the cone of the last 24 to prevent turning of the last about the last pin 26.

A horn 38 engageable within the heel end of the platform cover 18 is employed to exert a heelward thrust upon the platform cover. This horn, which is shaped to conform to the outline of the heel end of the shoe, is welded at its upper end to a lug extending from a collar 40 freely rotatable about a pin 42 secured in and extending between a pair of parallel arms 44. These arms 44 at their toeward (with respect to direction in which the shoe extends) ends are pivotally mounted upon a pin 46 and at their heelward

ends are pivotally mounted upon a pin 46 and at their heelward

ends are integrally joined by welding to a filler block positioned between them to form a finger grip 47. The pin 46 is secured in and extends through the intermediate portion of an arm 48 which is fulcrumed at its toeward end on a pin 50. The arm 48 extends downwardly and heelwardly between the arms 44 and is pivotally connected at its heelward end to a pin 52 which is secured in a wooden block 54. The block 54, which is about three-quarters of an inch thick, has formed in it a slot 56 to receive the arm 48, and the pin 52 bridges this slot. The block 54 is shaped to conform to the outline of the heel end of the shoe and at its heelward end is recessed to accommodate the thickness of the metal which forms the horn 38. The pin 50 is secured in and extends between the upper ends of a pair of parallel lever arms 58 (only the near one of which appears in the drawings) which extend downwardly upon opposite sides of the last 24 and which at their lower ends are fulcrumed upon a pin 60 secured in and extending transversely through the base 30. The arms 58 are long enough to bring the pin 50 about two inches above the sock lining 20 at the beginning of the operation and to enable it to clear the heel end of the last 24 when the arms 58 are swung heelwardly. A pair of spacing collars 62 preferably welded to the arms 58 engage the sides of the arm 48 to hold the arm 48 centered upon the pin 50. A tension spring 64 anchored at one end to a hook on the arm 48 and at its other end to a hook on the collar 40 tends to hold the arms 44 up against a stop 66 on the arm 48 and also to hold the lower end portion of the horn 38 against the block 54 and within the recess provided for it in the block. In this position the horn 38 extends down almost into contact with the sock lining 20. The lower edge of the horn 38 may be shaped to bring its central portion slightly closer to the sock lining than its lateral portions.

Fulcrumed upon each projecting end portion of the pin 60 is a segmental arm 68. These arms 68 embrace the base 30 and the standard 28 and also the arms 58, and they have heelwardly extending portions 70 which are bent toward each other and joined together at a locality heelward of the base and of the standard to form a lever arm. The heelward end of the arm formed by the extensions 70 is pivotally connected to the upper end of a treadle rod 12 which is normally held in an upper stopped position by the usual treadle spring (not shown). Secured upon the segmental portion of each of the arms 68 is a segmental block 74, these blocks 74 being capable of bearing against their respective adjacent arms 58 when the treadle is depressed to swing the arms 58 in a clockwise direction as viewed in the drawings. In order to provide a stop to limit the heelward swinging movement of the arms 58, the extensions 70 have shoulders or abutments 76 formed on their inner faces engageable with the arms 58.

The operation of the machine as so far described will now be explained. Initially the mechanism carried by the upper ends of the arms 58 occupies an out-of-the-way position as far to the heelward side of the machine as permitted by the engagement of the arms 58 with the stops 76. The operator begins by mounting the last 24 upon the last pin 26 with the toe end of the last pointed away from him to facilitate manipulation of the shoe parts upon the last. He then draws the partially completed shoe assembly by hand as far heelwardly upon the last as he con-

veniently can. Most shoes are loose enough to enable the heel strap 14 to be positioned over the heel end of the last without difficulty. However, if the shoe to be operated upon is unusually tight, the heel strap may be bent upward and laid over the forepart of the last. The operator then grasps the finger grip 47 and raises the mechanism associated with it well above the supporting pin 50 and swings this mechanism and also the arms 58 toewardly until the arms 58 occupy the positions in which they are shown in Fig. 1. The mechanism associated with the finger grip 47 is then let down to enable the block 54 to rest on the sock lining.

The operator then gently depresses the treadle to swing the arms 58 heelwardly until the horn 38 comes into engagement with the heel end of the pocket formed by the upturned platform cover 18. As the block 54 and the horn 38 are thus moved rearwardly the horn 38 engages and passes over the seam 22 until it engages the fold between this seam and the platform cover. The operator increases the downward pressure upon the treadle to urge the block 54 and the horn 38 rearwardly far enough to stretch the platform cover until its heel end overlies the heel end of the last as shown in Fig. 3. During this operation he may manipulate the upper of the shoe to facilitate its being drawn rearwardly, and to insure its proper positioning upon the last, by the tension on the sock lining. The operator may, when he considers it desirable, stretch the sock lining to bring its heel end somewhat beyond the end of the last. When he has stretched the sock lining to the desired extent and while holding it thus stretched by pressure on the treadle, the operator depresses the finger grip 47 to cause the horn 38 to turn the heel end of the platform cover 18 from the upstanding position shown in Fig. 3 to the reversed position shown in Fig. 4, wherein the platform cover hugs the heel end of the last and thereby prevents undesirable creeping of the sock lining and consequent loosening of the shoe upon the last. The horn 38 and the block 54, now free of the platform cover, ride off the heel end of the lasted shoe assembly as the arms 58 swing toward the operator into their out-of-the-way position. The last, with the shoe assembly on it, may now be removed from the last pin.

To prevent excessive stretching of the platform cover, the side and rear surfaces of the last 24 may be recessed to a depth substantially equal to the thickness of the material forming the platform cover, such recess being coextensive with the platform cover when the latter is turned down around the last.

The modified machine shown in Figs. 5 to 8, inclusive, is adapted for operation upon shoes having platform covers of flimsy material which might stretch unduly under the force exerted by the heelward thrusting member, thereby allowing the heelward thrusting member to ride over them without transmitting a heelward pull into the sock lining. This modified machine, as presently will be pointed out, is provided with means for clamping the platform cover against the heelward thrusting member to prevent yielding of the platform cover.

Certain of the members shown in Figs. 5 to 8, inclusive, are similar to corresponding members of the machine already described and are identified herein by like reference numerals. Such members consist of the shoe parts numbered 10 to 22, inclusive, the last 24, the last pin and its supporting structure numbered 26 to 34, inclu-

sive, the fulcrum pin 60 and the segmental arms together with their associated parts and treadle connections numbered 68 to 76, inclusive.

Extending upwardly from the projecting ends of the fulcrum pin 60 and embracing the base 30 are a pair of arms 100 which, unlike the arms 58, are not straight but which, at their upper portions, are arched toward each other over the last. Extending upwardly from each of the inner ends of the arched portions of the arms 100 is an ear 102. A short pivot pin 104 extends between and is carried by these ears.

A pair of parallel spaced links 106 are pivotally mounted at their toeward ends upon the pin 104, the links 106 being within the ears 102 and being adjacent respectively to the ears. The links 106 at their heelward ends are pivotally connected to a cross pin 108 to which also are pivotally connected the upper ends of a pair of sickle-shaped levers 110. These levers 110 extend downwardly and heelwardly from the pin 108 in parallel relation with a space of about one inch between them. A tension spring 112 is connected at one end to the midportion of the pin 108 and at its opposite end to a lug 113 projecting from an upstanding flange 114. This flange 114 is integral with and extends upwardly from the midportion of a metal plate 116 having an outline which, as seen in plan (Fig. 6), is generally similar to that presented by the heel seat portion of a last of ordinary shape. The plate 116 corresponds to the block 54 of the machine previously described.

A lost motion connection between the flange 114 and the pin 104 is provided in the form of a slot 118 formed in the flange 114 and so arranged that when the plate 116 is resting on the sock lining of a shoe to be operated upon the pin 104 may move to and fro along the slot without disturbing the position of the plate 116 heightwise. The flange 114 is centralized with respect to the pin 104 by means of spacer rings 120 (Fig. 6) of a diameter greater than the width of the slot 118 and disposed between the flange 114 and the links 106.

Extending through the flange 114 about a half inch below the lower edge of the slot 118 is a pin 122. The arched upper end portions of the arms 100 are high enough to clear the pin 122. On the opposite end portions of the pin 122 and closely adjacent to the opposite side faces of the flange 114 are pivotally mounted a pair of parallel arms 124 which constitute the toeward portion of a hand lever 126. The arms 124 extend heelwardly, in a direction approximately parallel to that of the links 106, between the sickle-shaped levers 110, to which they are pivotally connected by a pin 128. The location and the arrangement of the pin 104 and of the pins 108, 122 and 128 provide a more or less parallel-link motion for imparting a downward clamping movement to the sickle-shaped levers 110 on depression of the hand lever 126. The slot 118 permits swinging movement of the lever arm 100 in a clockwise direction as viewed in Figs. 5, 7 and 8 to swing the sickle-shaped levers 110 into a clamping position (as will presently be explained) without affecting the position of the plate 116.

Normally the spring 112 holds the plate 116 in such a position as to cause the left-hand or toeward end of the slot 118 to engage the pin 104, with the links 106 and the arms 124 in upraised position about the pin 104 and the pin 122 respectively and with the upper edges of the arms 106

124 abutting against stops 130 extending from opposite faces of the flange 114. In this position, as shown in Fig. 5, the whole assembly of parts carried by the pin 104 may be swung bodily about the pin 104 as a pivot by means of the hand lever 126 without changing the relative settings of the parts included in said assembly.

Mounted on the pin 128 for free pivotal movement is a horn 132 similar to the horn 38 of the machine shown in Figs. 1 to 4, inclusive. The lower edge portion of the horn 132 has a curvature similar to that of the outline of the heel end portion of the plate 116. It should be noted that the horn 132, unlike the horn 38, is not directly biased by spring action but hangs freely between the flange 114 and the sickle-shaped levers 110. When the spring 112 is contracted and the arms 124 are held against the stop 130 as shown in Fig. 5, the horn 132 is held raised with its bottom edge slightly above the level of the plate 116 and engaging a narrow sloping ledge 134 (Fig. 9) between the heelward edge of the flange 114 and the heelward end of the plate 116.

The lower end portions of the sickle-shaped levers 110 are integral with and are bridged by a block 136, the toeward face of which is concave and is substantially complementary to the convex outer surface of the horn 132. The sickle-shaped levers 110 together with the block 136 constitute a gripper device for clamping the heelward end of the platform cover 18 against the horn 132. The lower portion of the outer surface of the horn and the heelward edge of the plate 116 may be roughened by the provision of transverse serrations to augment their gripping action on the platform cover 18. The concave surface of the block 136 is preferably smooth to avoid marring that surface of the platform cover which is visible in the finished shoe.

The operation of the modified machine will now be explained. Initially, the mechanism carried by the pin 104 occupies an out-of-the-way position, determined by the stops 74, to the heelward side of the machine. The operator begins by mounting the last 24 upon the last pin 26 and drawing the partially completed shoe assembly by hand as far heelwardly upon the last as he conveniently can. He then grasps the lever 126 and raises the mechanism associated with it well above the pin 104 and swings this mechanism and also the arms 100 toewardly against the stops 74. The mechanism carried by the pin 104 is then let down to enable the plate 116 to rest upon the sock lining. When the parts are in this position, as shown in Fig. 5, the spring 112 will hold the block 136 well out of contact with the horn 132, leaving ample space for the platform cover 18 to project between these parts. The bottom edge of the horn 132 at this time is resting on the ledge 134.

The operator now gently depresses the treadle, causing the arms 100 to transmit a heelward thrust upon the links 106 to bring the horn 132 into engagement with the heel end of the upturned platform cover 18. As the platform cover tends to resist the heelward thrust of the horn 132, the pin 104 travels heelwardly along the slot 118, overcoming the tension of the spring 112 and causing the sickle-shaped levers 110 to swing in a clockwise direction about the pin 128. The gripper block 136 thus closes upon the heel end of the platform cover 18 and clamps it against the outer face of the horn 132, the horn itself being sustained against this clamp.

ing pressure, and also against the resistance of the platform cover, by the heelward edge of the flange 114. The block 136 and the horn 132 thus constitute a pair of grippers between which the platform cover is clamped. When the platform cover has been thus gripped and the swinging of the sickle-shaped levers 110 has been arrested, continued depression of the treadle causes the heelward thrust of the links 106 to transmit a corresponding pull on the arms 124, 10 this pull being transmitted to the flange 114 through the pin 122. The horn 132, and the gripper block 136 in clamping relation to the horn, are thus moved as a unit heelwardly and the heel end of the platform cover 18, being clamped between them, transmits a heelward tension into the sock lining 20 which serves to draw the shoe assembly heelwardly upon the last. The operator meanwhile has both hands free for smoothing the forepart of the upper and making such manual adjustments as may be required to insure proper assembly between the shoe and the last. The operator continues to depress the treadle until he sees that the heelward edge of the plate 116 has moved into register with or slightly beyond the heelward end of the sole plate on the last bottom and is in a position to permit the horn 132 to move down along the extreme heel end of the last. The positions of the several parts at this time are shown in Fig. 7, from which figure it will be seen that the platform cover is still held clamped between the horn 132 and the block 136.

In order to reverse the platform cover and bring it down into a position where it hugs the heel end of the last, the operator depresses the hand lever 126. During the initial downward movement of the hand lever 126 the horn 132 rides heelwardly off the ledge 134 and moves down past the heel end of the plate 116. Continued downward movement of the horn turns the platform cover down and causes it to hug the heel end of the last, as shown in Fig. 8. The downward movement of the lever 126 serves to rock the sickle-shaped lever 110 and the block 136 in a counterclockwise direction, as viewed in Figs. 7 and 8, thereby releasing the platform cover from their grip. The operator may aid in the opening of the gripper block 136 by slightly releasing the pressure on the treadle at the moment that he depresses the hand lever 126. After the platform cover 18 has been turned down around the sides of the last to retain the shoe assembly in lasted position, the operator raises the hand lever 126 to lift the plate 116 and its associated parts away from the shoe assembly and then swings them clear of the last by pulling the hand lever 126 toward him so as to cause the lever arms 106 to move into engagement with the abutments 76. The shoe assembly together with its last 24 may then be removed from the machine.

Having described my invention, what I claim as new and desire to secure by Letters Patent of the United States is:

1. In a force lasting machine, a support for a last on which is loosely mounted a partially completed shoe having at its heel end a platform cover turned heightwise away from the last, and means for first forcing the shoe heelwardly on the last and then for reversing heightwise the position of the heel end of the platform cover to cause the heel end of the platform cover to hug the heel end of the last and thereby prevent undesirable lengthwise creeping of the shoe and consequent loosening of the shoe on the last.

2. In a force lasting machine, a support for a last on which is loosely mounted a partially completed shoe having at its heel end a platform cover turned heightwise away from the last to form a pocket, a member engageable with the interior of the pocket formed by the platform cover, means for forcing said member heelwardly against the pocket to urge the shoe further on the last, and means for moving said member in a direction to reverse heightwise the position of the platform cover to cause the platform cover to hug the heel end of the last and thereby to prevent undesirable lengthwise creeping of the shoe and consequent loosening of the shoe on the last.

5 3. In a force lasting machine, a support for a last on which is loosely mounted a partially completed shoe having at its heel end a platform cover turned heightwise away from the last to form a pocket, a member engageable with the interior of the pocket formed by the platform cover, means for forcing said member heelwardly against the pocket to urge the shoe further on the last, and means for moving said member in a direction to reverse heightwise the position of the platform cover to cause the platform cover to hug the heel end of the last and thereby to prevent undesirable lengthwise creeping of the shoe and consequent loosening of the shoe on the last.

20 4. In a force lasting machine, a support for a last on which is loosely mounted a partially completed shoe having at its heel end a platform cover turned heightwise away from the last to form a pocket, a horn curved to conform to the outline of the heel end of a shoe and adapted to interior engagement with the pocket formed by the platform cover, means for moving the horn heelwardly against the pocket and for causing it to exert heelward pressure on the platform cover to urge the shoe further on the last, and means for moving the horn heightwise of the last to cause it to reverse heightwise the position of the platform cover, thereby causing the platform cover to hug the heel end of the last to prevent undesirable lengthwise creeping of the shoe and consequent loosening of the shoe on the last.

25 5. In a force lasting machine, a support for a last on which is loosely mounted a partially completed shoe having a platform cover stitched to its sock lining and turned heightwise away from the last to form a pocket at the heel portion, a member slidably toewards and heelwardly on the sock lining and having its heelward portion shaped to the outline of the heel end of a shoe, a horn curved to conform to the outline of the heel end of a shoe and adapted to be urged heelwardly by the slidably member into engagement with the pocket formed by the platform cover, means for sliding the slidably member heelwardly and for causing it to press the horn heelwardly against the platform cover to urge the shoe further on the last, and means for moving the horn heightwise of the last to cause it to reverse heightwise the position of the platform cover, thereby causing the platform cover to hug the heel end of the last to prevent undesirable lengthwise creeping of the shoe and consequent loosening of the shoe on the last.

30 6. In a force lasting machine, a support for an inverted last on which is loosely mounted a partially completed shoe having at its heel end a platform cover turned up from the last to form a pocket, a pair of grippers for clamping between them the platform cover, a pivotal connection about which one gripper can fulcrum into and out of clamping position relatively to the other, said pivotal connection being positioned above the last and the grippers extending down from the pivotal connection for engagement with the upstanding platform cover, and means for moving the grippers first into cover-clamping position and then heelwardly to urge the shoe further on the last.

35 7. In a force lasting machine, a support for a last on which is loosely mounted a partially completed shoe having at its heel end a platform cover turned heightwise away from the last to form a pocket, a member engageable with the interior of the pocket formed by the platform

cover, means for forcing said member heelwardly against the pocket to urge the shoe further on the last, and means for holding the platform cover against said member to prevent the platform cover from slipping away from said member while said member is being forced heelwardly.

7. In a force lasting machine, a support for a last on which is loosely mounted a partially completed shoe having at its heel end a platform cover turned heightwise away from the last to form a pocket, a horn curved to conform to the outline of the heel end of a shoe and adapted to interior engagement with the pocket formed by the platform cover, means for moving the horn heelwardly against the pocket and for causing it to exert heelward pressure on the platform cover to urge the shoe further on the last, means for moving the horn heightwise of the last to

cause it to reverse heightwise the position of the platform cover, thereby causing the platform cover to hug the heel end of the last to prevent undesirable lengthwise creeping of the shoe and consequent loosening of the shoe on the last, and means for holding the platform cover clamped against the horn to prevent the platform cover from slipping away from the horn while the horn is being moved heelwardly.
